US00D947851S

(12) **United States Design Patent** (10) Patent No.: **US D947,851 S**
(45) Date of Patent: ** Apr. 5, 2022

(54) **HOUSING MODULE FOR AN ELECTRONIC DEVICE**

(71) Applicant: **Apple Inc.**, Cupertino, CA (US)

(72) Inventors: **Jody Akana**, San Francisco, CA (US); **Molly Anderson**, San Francisco, CA (US); **Bartley K. Andre**, Palo Alto, CA (US); **Shota Aoyagi**, San Francisco, CA (US); **Anthony Michael Ashcroft**, San Francisco, CA (US); **Marine C. Bataille**, San Francisco, CA (US); **Jeremy Bataillou**, San Francisco, CA (US); **Abidur Rahman Chowdhury**, San Francisco, CA (US); **Sawyer Isaac Cohen**, Menlo Park, CA (US); **Clara Geneviève Marine Courtaigne**, Palo Alto, CA (US); **Markus Diebel**, San Francisco, CA (US); **Richard Hung**, **Minh Dinh**, Saratoga, CA (US); **Jonathan Gomez Garcia**, San Francisco, CA (US); **M. Evans Hankey**, San Francisco, CA (US); **Julian Hoenig**, San Francisco, CA (US); **Richard P. Howarth**, San Francisco, CA (US); **Jonathan P. Ive**, San Francisco, CA (US); **Julian Jaede**, San Francisco, CA (US); **Hugh J. Jay**, Mountain View, CA (US); **Duncan Robert Kerr**, San Francisco, CA (US); **Peter Russell-Clarke**, San Francisco, CA (US); **Benjamin Andrew Shaffer**, San Jose, CA (US); **Sung-Ho Tan**, San Francisco, CA (US); **Clement Tissandier**, San Francisco, CA (US); **Eugene Antony Whang**, San Francisco, CA (US); **Christopher R. Xydis**, San Francisco, CA (US); **Rico Zörkendorfer**, San Francisco, CA (US)

(73) Assignee: **Apple Inc.**, Cupertino, CA (US)

(**) Term: **15 Years**

(21) Appl. No.: **29/714,466**

(22) Filed: **Nov. 22, 2019**

(51) LOC (13) Cl. **14-02**

(52) U.S. Cl. **D14/439**

CLAIM

The ornamental design for a housing module for an electronic device, as shown and described.

DESCRIPTION

FIG. 1 is a bottom and front perspective view of a housing module for an electronic device showing the claimed design;
FIG. 2 is a top and rear perspective view thereof;
FIG. 3 is a front elevation view thereof;
FIG. 4 is a rear elevation view thereof;
FIG. 5 is a left side elevation view thereof;
FIG. 6 is a right side elevation view thereof;
FIG. 7 is a top plan view thereof; and,
FIG. 8 is a bottom plan view thereof.

The broken lines in the figures show portions of the housing module for an electronic device that form no part of the claimed design.

1 Claim, 6 Drawing Sheets

FIG. 3

FIG. 4

FIG. 5

FIG. 6

FIG. 7

FIG. 8
